EX

No. 13,422

Nov 14, 1882

UNITED STATES PATENT OFFICE.

JOHN L. POPE, OF CLEVELAND, OHIO.

DESIGN FOR A CARRIAGE-STEP.

SPECIFICATION forming part of Design No. 13,422, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for Carriage-Steps, of which the following is a specification, reference being had to the accompanying photographic illustration, forming part thereof.

This invention relates to a new design for carriage-steps; and it consists in ornamenting the tops or upper surface thereof with raised lines or work and forming a series of connecting star-shaped figures, as will hereinafter be more particularly specified and claimed.

15 In the accompanying photograph it will be observed that the raised rib-work of the carriage-step is so disposed or placed as to form a number of adjoining star figures, a peculiarity of which is that every one of the sides 20 or angles of each star is made to form a side or a portion of some other star adjacent, the general effect of all of which is the appearance of a number of diamond-shaped figures running in almost every direction.

At a will be found the center of one star, 25 which forms six radiating diamond-shaped figures, *bb*, &c., and in whichever direction the eyes are now turned they will observe an adjoining similarly-shaped star figure; and stars so made up of this ribbed work may be readily traced 30 out to near the edges of the step, where there is a raised border-line running around the whole extent thereof and forming obtuse angles at each corner.

What I claim as my new design, and desire 35 to secure by Letters Patent, is—

A design for a carriage-step, consisting of a series of adjoining stars made up of raised or ribbed work, substantially as shown and described.

40 In witness whereof I hereunto set my hand this 31st day of May, 1882.

JOHN L. POPE.

In presence of—

A. A. POPE,
C. M. COPP.
